(57) **CLAIM**

The ornamental design for a water toy, as shown and described.

DESCRIPTION

FIG. 1 is a front and top perspective view of a water toy, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated in FIG. 1; FIG. 10 is an enlarged view of a portion indicated in FIG. 2; and,

FIG. 11 is an enlarged view of a portion indicated in FIG. 4. The broken lines in the figures illustrate portions of the article that form no part of the claimed design. The dash dot dash lines in FIGS. 1, 2, 4 and 9-11 are for the purpose of depicting the boundary lines of the enlarged view and form no part of the claim.

1 Claim, 11 Drawing Sheets
